 tion of Massachusetts

Application June 6, 1936, Serial No. 83,973

15 Claims. (Cl. 51—95)

This invention relates to grinding machines, and more particularly to a fluid pressure operated wheel feeding mechanism.

One object of this invention is to provide a simple and thoroughly practical hydraulically operated wheel feeding mechanism for a grinding machine. Another object of this invention is to provide a suitable wheel feed control mechanism so that the infeeding movement of the grinding wheel may be precisely controlled so as to grind a work piece to a predetermined size. Another object of this invention is to provide a fluid pressure wheel feed control which enables a precise regulation of the infeeding movement and also the dwell after the infeeding movement has stopped. Other objects will be in part obvious or in part pointed out hereinafter.

This invention accordingly consists in the features of construction, combinations of elements, and arrangements of parts, as will be exemplified in the structure to be hereinafter described, and the scope of the application of which will be indicated in the following claims.

In the accompanying drawing in which is shown one of various possible embodiments of the mechanical features of this invention,

The figure is an end view of a grinding machine, having parts broken away and shown in section to more clearly show the operating construction.

A grinding machine has been illustrated in the drawing comprising a base 10 which supports a transversely movable wheel slide 11 which is mounted on transversely extending ways (not shown). The wheel slide 11 supports a rotatable grinding wheel 12 which is mounted on the end of a rotatable wheel spindle 13. The wheel spindle 13 may be driven by any of the well-known driving mechanisms, such as an overhead belt drive or an electric motor mounted on the wheel slide. As illustrated, a wheel driving pulley 14 is mounted on the opposite end of the wheel spindle 13 and is connected by a driving belt 15 with a source of power.

The base 10 also supports a longitudinally movable work supporting table 17 which is arranged to reciprocate longitudinally relative to the base 10 on a flat way 18 and a V-way 19. The table 17 is provided with a rotatable work support which may comprise a headstock 20 and a footstock (not shown), each of which is provided with work supporting centers to rotatably support a work piece 21 in operative relation with the grinding wheel 12.

The table 17 may be traversed longitudinally by a manually operable traverse mechanism 55 which includes a rack bar 25 depending from the

under side of the table 17. The rack bar 25 meshes with a gear 26 supported on the inner end of a rotatable shaft 27. A manually operable traverse wheel 28 is mounted on the outer end of the shaft 27 and is arranged to be manually rotated to traverse the table 17 longitudinally relative to the base 10. If desired, a power operated traversing or reciprocating mechanism may be provided, such as for example a mechanism of the type shown in the expired U. S. patent 10 to Norton No. 762,838 dated June 14, 1904.

A wheel feeding-mechanism is provided for manually feeding the grinding wheel toward and from the work, which comprises a half nut 35 depending from the wheel slide 11. The half nut 15 35 meshes with or engages a rotatable cross feed screw 36. A forwardly extending portion 37 of the cross feed screw 36 is slidably keyed to a rotatable sleeve 38. The rotatable sleeve 38 is formed as an integral part of a rotatable shaft, 20 which is journaled in bearings 39 and 40 in the base 10. A manually operable feed wheel 41 is mounted on the forward end of a stud 42. The stud 42 carries a pinion 43 which meshes with a gear 44 mounted on the outer end of the sleeve 25 38 so that a manual rotation of the feed wheel 41 serves to rotate the feed screw in either direction to cause a forward or rearward feeding movement of the grinding wheel 12 and wheel slide 11. The feed wheel 41 may be provided with 30 a micrometer adjusting mechanism 45 which is substantially identical with that shown in the above-mentioned prior patent to Norton. This micrometer mechanism serves to precisely adjust the stop on the manual infeed to compensate for 35 wheel wear.

In the preferred construction, the wheel slide 11 is arranged so that it may be moved toward and from the work piece to grind the same to a predetermined size by means of a fluid pressure actuated wheel feeding mechanism. As illustrated in the drawing, the rear end of the feed screw 36 is rotatably supported in a slidably keyed bearing 50 which is supported in a casing 51 on the base of the machine. A fluid pressure cylinder 49 is attached to the casing 51 and contains a slidably mounted piston 52 which is connected by a piston rod 53 with the bearing 50 and is arranged so that when fluid under pressure is admitted to a cylinder chamber 54, the piston 52 40 will be moved into its rearward position, as illustrated in the drawing, transmitting a corresponding movement through the feed screw 36, the half nut 35, to move the wheel slide 11 and the grinding wheel 12 rearwardly to an inoperative posi- 50 55

tion. Similarly, when fluid under pressure is admitted to a cylinder chamber 55, the wheel slide 11 and grinding wheel 12 are caused to move in a forward direction to move the grinding wheel 12 toward the work piece 21 for a grinding operation. When fluid is admitted either to the cylinder chamber 54 or the cylinder chamber 55, a rapid approaching or receding movement of the wheel 12 and wheel slide 11 is provided.

It is desirable to provide a suitable fluid pressure controlling or feed regulating mechanism for modifying the rapid approaching movement caused by the piston 52 to obtain a controlled and predetermined feeding movement of the grinding wheel. In the preferred construction, a self-contained dash pot feed regulator is provided comprising a pair of dash pot cylinders 56 and 57 which contain dash pot pistons 58 and 59 respectively. The dash pot pistons 58 and 59 and their respective cylinders 56 and 57 are arranged with their axes parallel to each other and spaced on diametrically opposite sides of the piston rod 53. The dash pot pistons 58 and 59 are normally held in a rearward position by means of springs 60 and 61 respectively. Adjustable stop screws 62 and 63 serve to respectively limit the rearward movement of the dash pot pistons 58 and 59.

The forward rapid feeding movement of the wheel 12 and wheel slide 11 continues until an adjustable sleeve 65, which is adjustably supported on the rear portion of the piston rod 53, engages the ends of the dash pot pistons 58 and 59 respectively, after which the rapid approaching movement of the wheel 12 and slide 11, as produced by the piston 52, is reduced to a slower predetermined grinding feed due to the fact that fluid confined within the dash pot cylinders 56 and 57, which are interconnected, exhausts fluid through a passage 66, a needle valve 67, into a reservoir 68 contained within the dash pot casing. By adjusting the aperture of the needle valve 67, a desired and predetermined infeed may be obtained.

When fluid under pressure is admitted to the cylinder chamber 54 to cause a rearward movement of the piston 52, the sleeve 65 moves rearwardly and the released tension of the springs 60 and 61 serves to return the dash pot pistons 58 and 59 respectively to the rearward position, as illustrated in the drawing. During the rearward movement of the dash pot pistons 58 and 59, a suction is created within the dash pot cylinders 56 and 57 respectively which serves to aid in drawing fluid from the reservoir 68, through a pipe 69 and a ball check valve 70, to fill the dash pot chambers 56 and 57 to fill the chambers for the next infeeding operation. During the infeeding movement of the dash pot pistons 58 and 59, the fluid within the dash pots 56 and 57 serves to hold the ball check valve 70 closed so that fluid within the dash pot cylinders 56 and 57 is forced out through the passage 66 and the needle valve 67 into the reservoir 68 to control the infeeding movement, as desired.

A fluid pressure system is provided to convey fluid under pressure to the cylinder 49. This system may comprise a reservoir 75 which is located preferably within the base of the machine and from which fluid is pumped by a geared pump 76, through a pipe 77, and through a pipe 78, to a control valve 79. The control valve 79 is of a balanced piston type comprising a valve stem 80 having formed integrally there-

on valve pistons 81, 82, 83 and 84. The front end of the valve stem 80 is provided with a spool shaped member 85 which is connected by a stud 86 with a pivotally mounted lever 87. The lever 87 is pivotally supported on a stud 88 which is supported on a bracket 89 on the base 10 of the machine. A manually operable control lever 90 is also pivotally mounted on the stud 88 and is connected to move the lever 87 when the manually operable lever is shifted to change the position of the control valve 79, as desired.

In the position of the parts, as illustrated in the drawing, the valve stem 80 is in its rearward position so that fluid under pressure passing through the pipe 78 enters a valve chamber 91 between the valve pistons 82 and 83 and passes through a passage 92, into cylinder chamber 54, to move the piston 52 rearwardly to withdraw the slide 11 and grinding wheel 12 from operative engagement with the work piece 21. During this movement, fluid is exhausted from the cylinder chamber 55, through a passage 93, through a valve chamber 94 between the valve pistons 82 and 81, and a pipe 95 which exhausts into the reservoir 75.

When the control lever 90 is moved in a counterclockwise direction, that is moved forwardly, the control valve 79 is shifted into a reverse position so that fluid under pressure passing through the pipe 78 and the valve chamber 91 passes through the passage 93, into cylinder chamber 55, to cause a forward feeding movement of the piston 52, the wheel slide 11 and the grinding wheel 12. During the forward feeding movement, fluid is exhausted from the cylinder chamber 54, through the passage 92, into a valve chamber 96 between the valve pistons 83 and 84 and out through the pipe 95 into the reservoir 75.

The infeeding movement of the grinding wheel under the control of the dash pot pistons 58 and 59 respectively continues until an adjustable stop sleeve 98 carried on the adjustable sleeve 65, which is in turn supported on the piston rod 53, engages a stop surface 99 on the end of the dash pot casing, thereby positively limiting or stopping the forward advancing movement of the wheel slide 11 and the grinding wheel 12.

It is desirable to provide a feed and dwell control mechanism which enables a precise adjustment of the final infeeding movement of the grinding wheel as well as to precisely control the extent of the dwell or finish grinding dwell, sparking-out or finish grinding period. In the preferred construction, a displacement cylinder is provided which serves to precisely regulate the exhaust of fluid from the dash pot cylinders 56 and 57 to control the infeed of the grinding wheel. When the dash pot pistons have been rendered ineffective by the stop sleeve 98 engaging the stop surface 99, the continued displacement of fluid within the displacement cylinder serves to control a dwell or sparking out or finish grinding period to accurately size the work to the required extent. As illustrated in the drawing, a displacement cylinder 100 is connected by a pipe 101 with a passage 102 which is connected to the dash pot cylinders 56 and 57. A slidably mounted displacement rod 103 is mounted within the displacement cylinder 100. The displacement rod 103 is arranged so that it may be moved longitudinally at a controlled rate so that when moved in one direction it serves to increase the effective capacity of the displacement cylinder 100 at a controlled rate 75

and when moved in the reverse direction serves to displace fluid within the cylinder 100 at a controlled rate. The displacement rod 103 may be moved by a suitable power operated mechanism such as, for example, a fluid pressure operated piston 104 which is slidably mounted within the cylinder 105. The admission of fluid under pressure to the cylinder 105 may be controlled independent of the hydraulic infeeding mechanism above described.

In the preferred construction, the cylinder 105 is arranged so that the piston 104 and the displacement rod 103 move in the same direction as the main piston rod 53 and is preferably controlled by the control valve 78 so that the piston 104 moves in the same direction as, and in a definite timed relationship with, the wheel feed piston 52. The cylinder 105 is provided with cylinder chambers 106 and 107. In the position 20 of the parts, as illustrated in the drawing, fluid under pressure passing through the pipe 78 into cylinder chamber 91 passes through the passage 92 into the cylinder chamber 54 to cause a rearward movement of the piston 52 and also passes 25 through a pipe 108, through a ball check valve 109, and a pipe 110, into the cylinder chamber 106 to move the piston 104 toward the right into the position illustrated in the drawing. During the movement of the piston 104 toward the right, 30 fluid is exhausted from the cylinder chamber 107, through a pipe 115, into the valve chamber 94 and out through the pipe 95, into the reservoir 75.

When the reversing valve 79 is shifted into its 35 reverse position so that fluid under pressure within the valve chamber 91 passes through the passage 93 to cause a forward approaching movement of the piston 52, fluid under pressure also passes from the valve chamber 91, through the 40 pipe 115, into the cylinder chamber 107, to cause the piston 104 and the displacement rod 103 to move toward the left, as viewed in the drawing. In the preferred construction, the movement of the piston 104 toward the left is preferably at a 45 controlled rate so that the movement of the displacement rod 103 on the infeeding stroke may be accurately and precisely controlled. During the movement of the piston 104 toward the left, fluid exhausts from the cylinder chamber 106, through 50 the pipe 110, and closes the ball check valve 109. Due to the closing of the ball check valve 109, fluid under pressure passes through the pipe 111 and an adjustable throttle valve 112 and through the pipe 108, into the valve chamber 93, and out 55 through the pipe 95, into the reservoir 75.

A dwell control mechanism is provided for regulating and controlling the extent of the sparking-out or finish grinding time after the stop sleeve 98 engages the stop surface 99. This mechanism comprises a normally open mercury switch 120 which is carried by a supporting bracket 121 pivotally mounted on a stud 122 on a bracket 123 fixed to the base 10 of the machine. The mercury switch 120 is connected to the power lines 124. A solenoid 125 is connected in the electrical circuit in series with the normally open mercury switch 120. The solenoid 125 is connected by a link 126 with a stud 127 on the arm 87 and is arranged so that when the mercury switch 120 is rocked in a counterclockwise direction, the circuit is closed to energize the solenoid 125, thereby shifting the lever 87 and the lever 90 in a clockwise direction into the position illustrated in the drawing to shift the valve stem 80 of the control valve 79 so as to reverse the flow of fluid within

the system and cause a rearward movement of the grinding wheel 12 and the wheel slide 11.

In order to control the movement of the mercury switch 120, a fluid pressure mechanism is provided which is preferably connected with the displacement cylinder 100. This mechanism comprises a cylinder 130 having a piston 131 slidably mounted therein. A pipe 132 connects the cylinder 130 with the displacement cylinder 100. A spring 133 serves to normally hold the piston 131 in the position illustrated in the drawing. The spring 133 is preferably interposed between a casing 134 and a bracket 135 which is fixed to the end of the piston 131. An adjustable stop screw 138 in the casing 134 serves to limit the movement of the piston 131 toward the left, as viewed in the drawing.

In order to actuate the mercury switch 120 in timed relation with the movement of the piston 131, an adjustable detent 140 is mounted on the piston bracket 135. The detent 140 is arranged to engage a pivotally mounted detent 141 which is pivotally mounted on the stud 122. A downwardly extending projection of the pivotally mounted detent 141 is arranged in the path of the detent 140 so that when the detent 140 is moved toward the left, the pivotally mounted detent 141 rocks on the stud 122 and transmits no movement to the mercury switch 120. When the detent 140 is carried by piston 131 in a direction toward the right into the position illustrated in Fig. 1, the detent 140 striking the downwardly extending projection of the detent 141 serves to rock the bracket 121 and the mercury switch 120 in a counterclockwise direction, tipping the switch 120 and closing the circuit so as to energize the solenoid 125 and shift the lever 87, the lever 90, together with the valve 79, into the position illustrated in the drawing.

The first portion of the dash pot movement, 40 while fluid may exhaust through passage 66, serves to produce a controlled infeed to grind a shoulder on the work piece 21, and the displacement cylinder 100 together with the mercury switch 120 and its associated parts serves to control the final grinding operation as well as the dwell or sparking-out period at the end of the grinding operation.

In the operation of this improved wheel feeding mechanism, the work piece 21 is mounted in place in the machine, the work is rotated and the grinding wheel is rotated at a grinding speed. Assuming the feed mechanism to have been previously adjusted to the desired extent to obtain the desired infeeding movement, the manually operable control lever 90 is moved in a counterclockwise direction, as shown in Fig. 1, to shift the valve stem 80 so as to reverse the flow of fluid in the mechanism. The valve 78 is shifted so that fluid under pressure from pump 76 passing through pipe 78 into valve chamber 91 passes out through passage 93 into cylinder chamber 55 to cause a rapid approaching movement of the slide 11 and the grinding wheel 12 toward the work. The rapid approaching movement of the grinding wheel continues until the sleeve 65 carried by the piston rod 53 engages the ends of the dash pot pistons 58 and 59 and continued movement of the piston 52 is modified to produce a slow shoulder feed in which the fluid is exhausted from the dash pot chambers 56 and 57 through passage 66 and needle valve 67 into the reservoir 68. At the same time, when the pistons 58 and 59 are picked up by the sleeve 65, fluid from the dash pot cylinders 56 and 57 is forced through pipe 75

101 into the displacement cylinder 100 and through the pipe 132 into cylinder 130 to move the piston 131 toward the left, as viewed in the drawing, against the tension of the spring 133 5 until the piston 131 engages the stop screw 136. During this movement of the piston 131, the detent 140 rides idly by the detent 141 so as to render the dwell control mechanism operative.

During the forward movement of the slide 11 10 and grinding wheel 12, when the piston 52 starts moving fluid under pressure is also admitted from the valve 79, through pipe 115, into the cylinder chamber 107, to cause a movement of the piston 104 and the displacement rod 103 to 15 ward the left, as viewed in the drawing, as controlled by the aperture of the throttle valve 112. After the passage 66 is cut off, fluid from the dash pot chambers 56 and 57 may be forced only through the pipe 101, as permitted by the 20 controlled movement of the displacement rod 103 which serves to increase the fluid capacity of the cylinder 100 and at the same time fluid being forced through the pipe 101 serves to hold the piston 131 in a position toward the left. 25 This controlled infeeding movement for grinding the cylindrical portion of the work continues until the adjustable stop sleeve 98 engages the stop surface 99, thereby preventing further displacement of fluid within the dash pot cylinders 56 30 and 57. The displacement rod 103 continues to move toward the left and due to the compression of the spring 133, fluid within the cylinder 130 is forced through the pipe 132 into the displacement cylinder 100, as permitted by the 35 withdrawal of the displacement rod 103. This movement continues until the detent 140 engages the depending projection of the detent 141 as the piston 131 moves toward the right and rocks the bracket 121 and the mercury switch 120 in 40 a counterclockwise direction to make the circuit, thereby energizing the solenoid 125. The energizing of the solenoid 125 serves to move the lever 87 in a clockwise direction, thereby shifting the piston rod 80 and valve 79 into the position 45 of the parts illustrated in the drawing so as to admit fluid under pressure from the valve chamber 91, through passage 92, into the cylinder chamber 54 to cause a rapid rearward movement of the grinding wheel 12 and the wheel 50 slide 11.

When the valve 79 is shifted to reverse the movement of the piston 52, fluid under pressure also passes through the pipe 108, ball check valve 109, pipe 110, into cylinder chamber 106, to cause 55 the piston 104 and the displacement rod 103 to move toward the right. This movement displaces fluid within the displacement cylinder 100, passing it through the pipe 101 and into the dash pot cylinders 56 and 57 so that exhaust of fluid through the pipe 101 and fluid passing 60 through the pipe 69 and ball check 70 serves to fill the dash pot chambers 56 and 57 so that they are ready for the next infeed grinding operation.

The operation of the feed mechanism above described provides a shoulder grinding feed. In 65 case it is desired to grind work requiring no shoulder grinding feed, the needle valve 67 may be closed so as to prevent escapement of fluid from the dash pot pistons 56 and 57 through the passage 66 and needle valve 67 into the reservoir 70 68. In this case, when the adjustable sleeve 65 picks up and moves the dash pot pistons 58 and 59, fluid within the dash pot chambers 56 and 57 is forced out through the pipe 101 into the 75 displacement cylinder 100. The initial move-

ment of fluid through the pipe 101 into the displacement cylinder 100 passes through the pipe 132 into the cylinder 130 to move the piston 131 against the spring 133 so that the detent 140 is moved into a position for a dwell control operation. The infeeding movement continues at a controlled rate due to the controlled movement of the displacement rod 103 until the sleeve 98 engages the stop surface 99, thereby preventing further forcing of fluid from the dash pot cylinders 56 and 57 through the pipe 101. As the rod continues its movement toward the left, the compression of the spring 133 moves the piston 131 toward the right. This movement continues until the detent 140 engages the downwardly extending projection of the detent 141 to rock the mercury switch 120 so as to energize the solenoid 125 and thereby shift the reverse valve 79 into its reverse position to cause a rapid movement 15 of the grinding wheel 12 to an inoperative position. 20

It will thus be seen that there has been provided by this invention apparatus in which the various objects hereinabove set forth together with many thoroughly practical advantages are 25 successfully achieved. As many possible embodiments may be made of the above invention and as many changes might be made in the embodiment above set forth, it is to be understood that all matter hereinbefore set forth or shown 30 in the accompanying drawing is to be interpreted as illustrative and not in a limiting sense.

I claim:—

1. A grinding wheel feeding mechanism for a 35 grinding machine having a rotatable work support and a rotatable grinding wheel which are movable longitudinally and transversely relative to each other, a transversely movable slide to support one of said elements for movement toward and from the other, a fluid pressure piston and cylinder operatively connected to move said slide and cause a rapid relative movement of the wheel and work supports toward and from each other, and a wheel feed regulating mechanism for a grinding machine comprising a fluid pressure displacement cylinder, a displacement rod 40 slidably mounted therein to increase or decrease the fluid capacity of said cylinder, and a power operated means positively to move said displacement rod in either direction.

2. A grinding wheel feeding mechanism for a 45 grinding machine having a rotatable work support and a rotatable grinding wheel which are movable longitudinally and transversely relative to each other, a transversely movable slide to support one of said elements for movement toward and from the other, a fluid pressure piston and cylinder operatively connected to move said slide and cause a rapid relative movement of the wheel and work support toward and from each other, and a wheel feed regulating mechanism for a grinding machine comprising a fluid pressure displacement cylinder, a displacement rod 50 slidably mounted therein to increase or decrease the fluid capacity of said cylinder, power operated means positively to move said displacement rod in either direction, and means to regulate the speed of movement of said rod in one direction to control the infeeding movement of a 55 grinding wheel.

3. A grinding wheel feeding mechanism for a 60 grinding machine having a rotatable work support and a rotatable grinding wheel which are movable longitudinally and transversely relative to each other, a transversely movable slide to 65

support one of said elements for movement toward and from the other, a fluid pressure piston and cylinder operatively connected to move said slide and cause a rapid relative movement of the wheel and work support toward and from each other, and a wheel feed regulating mechanism for a grinding machine comprising a fluid pressure displacement cylinder, a displacement rod slidably mounted therein to increase or decrease the fluid capacity of said cylinder, and fluid pressure operated means including a piston and cylinder operatively connected to move said displacement rod at a controlled rate in either direction.

15 4. A grinding wheel feeding mechanism for a grinding machine having a rotatable grinding wheel, a transversely movable slide therefor, a fluid pressure piston and cylinder operatively connected to move said slide and wheel rapidly 15 toward and from the work, and a wheel feed regulating mechanism for a grinding machine comprising a fluid pressure displacement cylinder, a displacement rod slidably mounted therein to increase or decrease the fluid capacity of said 20 cylinder, means including a fluid pressure operated piston and cylinder to move said displacement rod in either direction at a controlled rate, and means including a control valve to admit fluid under pressure to either end of said cylinder.

25 5. A grinding wheel feeding mechanism for a grinding machine having a rotatable grinding wheel, a transversely movable slide therefor, a fluid pressure piston and cylinder operatively connected to move said slide and wheel rapidly 30 toward and from the work, and a grinding wheel feed regulating mechanism for a grinding machine comprising a dash pot piston and cylinder which are arranged to control the grinding infeed, a displacement cylinder, fluid connections 35 therebetween, a displacement rod slidably mounted within said displacement cylinder, and means to withdraw said rod from said displacement cylinder at a controlled rate to permit a controlled displacement of fluid from the dash pot cylinder.

40 6. A grinding wheel feeding mechanism for a grinding machine having a rotatable grinding wheel, a transversely movable slide therefor, a fluid pressure piston and cylinder operatively connected to move said slide and wheel rapidly 45 toward and from the work, and a grinding wheel feed regulating mechanism for a grinding machine comprising a dash pot piston and cylinder arranged to control the grinding infeed, a displacement cylinder, fluid connections therebetween, a displacement rod slidably mounted 50 within said displacement cylinder, and means including a fluid pressure operated piston and cylinder to withdraw said rod from said displacement cylinder at a controlled rate to permit a 55 controlled displacement of fluid from the dash pot cylinder.

7. A grinding wheel feeding mechanism for a grinding machine having a rotatable grinding wheel, a transversely movable slide therefor, a fluid pressure piston and cylinder operatively connected to move said slide and wheel rapidly toward and from the work, and a grinding wheel feed regulating mechanism for a grinding machine comprising a dash pot piston and cylinder arranged to control the grinding infeed, a displacement cylinder, a displacement rod which is 60 slidably mounted within said displacement cylinder, means including a fluid pressure operated piston and cylinder to move said displacement rod in either direction, and a control valve to con-

trol the admission of fluid to either end of said cylinder.

8. A grinding wheel feeding mechanism for a grinding machine having a rotatable work support and a rotatable grinding wheel which are 5 movable longitudinally and transversely relative to each other, a transversely movable slide to support one of said elements for movement toward and from the other, a fluid pressure piston and cylinder operatively connected to move said 10 slide and cause a rapid relative movement of the wheel and work support toward and from each other, a control valve to control the admission of fluid to said cylinder, and a wheel feed regulator comprising a dash pot piston and cylinder 15 which are arranged to modify the movement of said piston and cylinder, means including a displacement cylinder operatively connected with the dash pot cylinder, a displacement rod within said cylinder, means to withdraw said displacement 20 rod to allow displacement of fluid from said dash pot cylinder, and means to regulate the speed of movement of said displacement rod to facilitate adjustment of the displacement of fluid from said dash pot to control the infeeding 25 movement of the grinding wheel.

9. A grinding wheel feeding mechanism for a grinding machine having a rotatable grinding wheel and a transversely movable wheel slide, a fluid pressure mechanism comprising a piston and cylinder operatively connected to move said slide and grinding wheel rapidly either toward or from a work piece, and a wheel feed regulator including a dash pot piston and cylinder which is arranged to reduce the rapid approaching movement of the slide to a slow controlled infeeding movement, a displacement cylinder operatively connected with the dash pot cylinder, a displacement rod slidably mounted within said cylinder, and means to move said displacement rod at a controlled rate to control the displacement of fluid from said dash pot so as to control the infeeding movement of the grinding wheel.

10. A wheel feeding mechanism for a grinding machine having a rotatable grinding wheel, a transversely movable slide to support said wheel, means including a fluid pressure piston and cylinder to move said slide rapidly in either direction, a fluid pressure feed regulator to modify said rapid movement in one direction, a feed regulator and dwell control mechanism associated therewith including a displacement cylinder having a slideable displacement rod therein, said displacement cylinder being connected to receive the exhaust of fluid from said feed regulator, means to move said displacement rod at a controlled rate in either direction to regulate the speed of movement of the grinding wheel, and means including an electric switch actuated in timed relation with the movement of the displacement rod to automatically cause a rearward movement of the slide after a predetermined period of dwell.

11. A grinding wheel feeding mechanism for a grinding machine having a rotatable grinding wheel, a transversely movable wheel slide, a fluid pressure system including a piston and cylinder to move said slide, a control valve to admit fluid to either end of said cylinder to cause a rapid forward or rearward feeding movement of the grinding wheel, manual means to actuate said valve, a solenoid to shift said valve to cause a rapid rearward movement of said wheel, and a wheel feed regulator which is arranged to modify the movement of said piston including a dis-

- placement cylinder and a movable displacement rod to regulate the exhaust of fluid from said feed regulator, means to move said rod in either direction so as to control the fluid exhausted from said regulator and thereby control the infeeding movement of the grinding wheel, an adjustable stop mechanism to positively limit the forward feeding movement of the grinding wheel, a normally open electric switch which is normally 5 ly in an open position, and means actuated in timed relation with the movement of said displacement rod to actuate said switch and thereby energize said solenoid to reverse the control valve after a predetermined period of dwell. 10
15. 12. A grinding wheel feeding mechanism for a grinding machine having a rotatable grinding wheel, a transversely movable slide therefor, a fluid pressure piston and cylinder operatively connected to move said slide and wheel rapidly 20 toward and from the work, and a wheel feed regulating mechanism for grinding machines comprising a fluid pressure displacement cylinder, a displacement rod which is slidable therein to increase or decrease the fluid capacity of said 25 cylinder, means including a fluid pressure piston and cylinder to move said displacement rod in either direction, a control valve to admit fluid under pressure to either end of said cylinder, a manually operable lever to move said valve in either 30 direction, a solenoid to shift said valve to cause a rearward movement of the grinding wheel, a throttle valve in said system to control the speed of movement of the displacement rod in one direction, an electric switch, and fluid 35 pressure means actuated in timed relation with movement of said rod to actuate said switch so as to energize the solenoid and reverse said valve to cause a rapid rearward movement of the grinding wheel. 40
45. 13. A wheel feed regulating mechanism for a grinding machine having a transversely movable rotatable grinding wheel comprising a fluid pressure displacement cylinder, a displacement rod which is slidably mounted therein and arranged to increase or decrease the fluid capacity of said 50 cylinder, means including a fluid pressure piston and cylinder to move said displacement rod in either direction, a control valve to admit fluid to either end of said cylinder, a throttle valve in said system to control the speed of movement of the displacement rod in one direction to control the infeeding movement of the grinding wheel. 50
14. A wheel feed regulating mechanism for a
- grinding machine comprising a fluid pressure displacement cylinder, a displacement rod which is slidably mounted therein and arranged to increase or decrease the fluid capacity of said cylinder, means including a fluid pressure piston and cylinder to move said displacement rod in either direction, a control valve to admit fluid to either end of said cylinder, a manually operable lever to move said valve in either direction, a solenoid to shift said valve to cause movement of the piston, a throttle valve in said system to control the speed of movement of the displacement rod in one direction, an electric switch, and fluid pressure means actuated in timed relation with the movement of said displacement rod to close 15 said switch and energize said solenoid to reverse the control valve after a predetermined period of dwell. 20
15. A grinding wheel feeding mechanism for a grinding machine having a rotatable work support and a rotatable grinding wheel which are movable longitudinally and transversely relative to each other, a transversely movable slide to support one of said elements for movement toward and from the other, a fluid pressure piston and cylinder operatively connected to move said slide and cause a rapid relative movement of the wheel and work support toward and from each other, a control valve to admit fluid to either 25 end of said cylinder to cause a rapid forward and rearward feeding movement of the grinding wheel, manual means to actuate said valve, means including a solenoid to shift said valve to cause a rapid separating movement of said slide, a feed regulator which is arranged to modify the feeding movement of said piston including a displacement cylinder and a movable displacement rod to regulate the exhaust of fluid from said feed regulator, means to move said rod in either direction so as to control the exhaust of fluid 30 therefrom and control the infeeding movement between the grinding wheel and work support, an adjustable stop mechanism to positively limit the infeeding movement, means including a hydraulically actuated electric switch, and means actuated after the positive stop has been reached to displace fluid within said latter mechanism to actuate said switch after a predetermined period of dwell and operate said solenoid to reverse the valve and cause a rapid separating movement 35 between the wheel and work. 40
45. 16. A wheel feed regulating mechanism for a
- grinding machine comprising a fluid pressure displacement cylinder, a displacement rod which is slidably mounted therein and arranged to increase or decrease the fluid capacity of said cylinder, means including a fluid pressure piston and cylinder to move said displacement rod in either direction, a control valve to admit fluid to either end of said cylinder, a manually operable lever to move said valve in either direction, a solenoid to shift said valve to cause movement of the piston, a throttle valve in said system to control the speed of movement of the displacement rod in one direction, an electric switch, and fluid pressure means actuated in timed relation with the movement of said displacement rod to close 50 said switch and energize said solenoid to reverse the control valve after a predetermined period of dwell. 50
